UNITED STATES PATENT OFFICE.

COLEMAN B. WARREN, OF NORFOLK, VIRGINIA.

SHOULDERING ATTACHMENT.

Application filed May 29, 1928. Serial No. 112,648.

My invention has for its purpose to enable dentists to prepare quickly and easily teeth for porcelain jacket crowns.

The invention comprises a tool adapted to be used with the usual hand piece of a dental drilling engine, and provided with milling cutters, of the sleeve type, specially designed and quickly detachable, the tool having provisions whereby the cutter may be given a simple rotational movement or a combined rotation and reciprocation in order to make the shoulder conform to the general outline of the gum both anterior, posteriorly, mesio, distally, thereby producing an ideal shoulder for porcelain jacket crown restoration.

With other objects in view, the invention also resides in those novel details of construction, combination and arrangement of parts, all of which will be first fully described, then be specifically pointed out in the appended claims and illustrated in the accompanying drawing, in which:

Figure 1 is a perspective view of my device ready for use, its position when attached to a dental hand piece being indicated in dotted lines.

Figure 2 is an inverted plan view of the device shown in Figure 1, the cutter being removed.

Figure 3 is an enlarged cross section on the line 3—3 on Figure 2, looking in the direction of the arrow.

Figure 4 is a view similar to Figure 3 with a cutter in place and with a depth gauge non-conductor tip in position.

Figure 5 is a section on the line 5—5 of Figure 3.

Figure 6 is a detail perspective view of the cutter driving head.

Figure 7 is a detail view of the first used cutter and a tooth which has been partially cut by it.

Figure 8 is a detail view of the second used or finishing cutter and a tooth, the cut of which has been completed by the same.

Figure 9 is a view of the tooth shown in Figure 8 taken at right angles to the position of Figure 8.

In the drawing in which like numerals of reference indicate like parts in all of the figures, 1 represents the housing which has the drilled projection 2 for the reception of the worm 3, the projection having its ends tapped to receive respectively the bearing screw 4 and the hand piece socket 5, the lat-

ter having a bearing 6 for the worm shaft 7.

The socket 5 for receiving the hand piece of the dental drilling engine is provided with spring holding tongues 8 for the usual purpose.

The housing 1 has a socket 9 for the reception of the bearing sleeve 10 which holds the worm gear 12 in place, the worm gear 12 having a bearing 11 in the housing 1 while the sleeve 10 has a bearing shoulder 13 for the worm gear.

A light spring 14 is carried by the bearing sleeve to hold the cutter driving head 15 against dropping out.

The cutter driving head 15 has slots 16 to fit the worm gear lugs 17 so that the cutter driving head may be turned with and by the worm gear and still be free for reciprocating movement along its axis for a purpose presently to appear.

The cutter driving head 15 is provided with a shallow annular groove 18 on its periphery and with a cam groove 19. The groove 18 is designed to receive the light spring 14 to prevent the cutter driving head from leaving its bearing sleeve 10 accidentally.

The cutter driving head 15 has a bore 20 into which projects a driving pin 21, the bore 20 being adapted to receive the shank 36 of the cutters hereinafter referred to.

22 is a depth gauge consisting of a threaded pin with milled head that screws into the housing 1 and projects along the axis of the worm gear and the cutter driving head, projecting through the cutter driving head into the cutter where it may receive a tip 23 having a springy split sleeve 24 to hold it on the depth gauge and having an insulating pad 25 of hard rubber or the like to engage a sensitive tooth.

A thumb screw 26 is provided on which is a sliding collar 27, the thumb screw 26 projecting through a slot 28 in the housing and being threaded into a threaded aperture in the bearing sleeve 10, the thumb screw being shouldered so that it may be screwed tight to the sleeve 10, if desired. The collar 27 is used for the purpose of providing a square shoulder on the non-circular housing for the thumb screw 26.

The thumb screw 26 is drilled to receive the headed engaging pin 29, the head of which is adapted to lie in a countersunk portion of the head of the thumb screw. The engaging pin is provided with two an-

nular recesses spaced apart, as indicated, and having for their purpose the reception of a latching pin 30, the latching pin 30 being held to its latching position by means 5 of a light spring 31 which lies in the groove 32 of the head of the thumb screw 26. The thumb screw head is countersunk at 33 to receive the head of the engaging pin 29 and the head of the engaging pin 29 may be 10 provided with recesses as may also the head of the thumb screw in order that a sharp instrument or the thumb nail may be placed beneath the head of the engaging pin so that it can be brought out in order to disconnect 15 it from the cam groove 19 of the cutter driving head when it is desired that the cutter driving head shall undergo rotative movement only.

In connection with my invention I provide 20 sets of cutters, there being two cutters to a set, and the sets being made with pairs of cutters of different sizes to meet the requirements of practice. The first cutter 35 it will be seen is a milling cutter of the 25 sleeve type having a bayonet slotted shank 36 by means of which it may be secured to the cutter driving head. This cutter 35 is provided with cutting teeth on its periphery and it is also provided interiorly with flutes, 30 the flutes 37 being very shallow, just enough to give cutting clearance.

The second cutter of the set numbered 38 in the drawing is the finishing cutter. This cutter is provided with diametrically opposite 35 sets of cutting points 39 with square portions between the same. It is of the same diameter inside and out but is not fluted inside as is the cutter 35.

40 designates the tooth, showing the same as cut by means of the cutter 35 and 41 designates the same tooth after the cut has been finished by use of the cutter 39.

In using my invention, the cutter 38 is first employed, the depth gauge being set 45 to permit this cutter to make its cut to the required depth. When using the cutter 35, the engaging pin 29 is withdrawn from the cam slot 19 of the cutter driving head and a simple rotary movement is imparted to the 50 cutter. As soon as the preliminary cut has been made by this cutter 35 it is removed and the finishing cutter 38 put in its place. The engaging pin 29 is then pressed inwardly so as to enter the cam slot 19 whereby when the shaft 7 is turned the cutter 38 55 will receive not only a rotational movement on its axis but a reciprocating movement as well, thus giving to the remainder of the cut an undulated form, as shown on the tooth 60 41 in the drawing.

It will be noted that the engaging pin 29 is free to turn on its axis and thus acts as a roller in the cam groove 19, thereby reducing friction and wear at the point of 65 contact.

From the foregoing, it will be seen that the bearing for the engaging pin 29, i. e., the thumb screw 26, may be rotated through one-fourth of the circumference of the housing and can be clamped at any point within 70 the arc, making it possible for the operator to time the oscillations or reciprocations of the cutter without having to hold the hand piece in an awkward position. In other words, he can adjust the position of the cutter with respect to the position of the hand piece so that the undulations will be cut in the required or desired position on the tooth without changing the position of the hand piece from that position which the operator 75 may find most convenient.

The depth gauge that passes through the center of the housing is provided, as before stated, with an insulated tip, this tip being adapted to rest on the tooth being prepared 80 and the depth gauge screw ensures a satisfactory rest as well as a gauge for the depth of the shoulder being milled.

The relative speed of the cutter is slow, making the cutting easy to control and at the 85 same time keeping the heat created by the cutting friction at a minimum. The purpose of the up and down movement of the cutter is to permit the shoulder to conform to the general outline of the gum, both anterior, 90 posteriorly, mesio and distally, and thus produces, as before stated, an ideal shoulder for porcelain jacket crown restoration.

From the foregoing description, taken in connection with the accompanying drawings, 100 it is thought the construction, operation and uses of my invention will be readily clear to those skilled in the art.

What I claim is:

1. In a device of the character described, 105 a housing, a cutter driving head, a cutter carried by the driving head, means for mounting said head within said housing for rotational and reciprocatory motion, a driving shaft and driving gearing between said shaft and said cutter driving head to rotate said cutter driving head and said cutter around a common axis, and means engaging said cutter head and said casing to cause said cutter to be reciprocated along its axis 110 as it is being rotated around its axis, thereby giving the cutter a vibratory motion around its axis.

2. In a device of the character described, 115 a housing, a cutter driving head, a cutter carried by the driving head, means for mounting said head within said housing for rotational and reciprocatory motion, a driving shaft and driving gearing between said 120 shaft and said cutter driving head to rotate said cutter driving head and said cutter around a common axis, and means engaging said cutter head and said casing to cause said cutter to be reciprocated along its axis 125 as it is being rotated around its axis, there- 130

by giving the cutter a vibratory motion around its axis, and means to adjust the position of said mounting means with respect to the general position of the instrument whereby to vary the location of the cut surfaces and thereby adjust the position thereof with respect to the position in which the instrument is held.

3. In a device of the class described, a housing, a worm gear mounted for rotation within the housing, a worm shaft cooperating with the gear, a cutter driving head journalled in the housing and connected to said worm gear to rotate with it, a sleeve type milling cutter carried by said head, and means associated with said housing and said cutter driving head to cause said driving head to reciprocate along its axis as it is being turned on its axis by the worm gear, thereby causing said cutter to cut an undulating surface.

4. In a device of the class described, a housing, a worm gear mounted for rotation within the housing, a worm shaft cooperating with the gear, a cutter driving head journalled in the housing and connected to said worm gear to rotate with it, a sleeve type milling cutter carried by said head, means associated with said housing and said cutter driving head to cause said driving head to reciprocate along its axis as it is being turned on its axis by the worm gear, thereby causing said cutter to cut an undulating surface, and means for adjusting said last named means to alter the position of the undulations with respect to the general position in which the instrument is held, for the purposes specified.

5. In a device of the character described, a housing, a cutter driving head mounted in said housing for rotation on its axis and for reciprocation in the direction of its axis, means for driving said cutter head and means cooperating with said driving means to impart to said cutter head a combined rotational and reciprocatory motion, and a sleeve type milling cutter having separated cutting points, connected to said driving head whereby said cutter will cut an undulating surface.

6. In a device of the character described, a housing, said housing having a chamber, a worm gear rotatably mounted in said chamber, a driving worm shaft with worm mounted in said housing to drive said worm gear, a bearing sleeve rotatably mounted in said housing chamber, a cutter driving head rotatably mounted in said sleeve and connected with said worm gear for rotation with the same, said cutter driving head connection with the worm gear having provision permitting reciprocation of the cutter driving head along its axis, said cutter driving head having a cam slot, an engaging pin carried by said sleeve and entering said slot,

means for securing said sleeve against rotation, all being arranged whereby as said cutter driving head is rotated by said worm gear said pin and cam slot will cause reciprocation of the cutter driving head along its axis for the purposes specified.

7. In a device of the character described, a housing, said housing having a chamber, a worm gear rotatably mounted in said chamber, a driving worm shaft with worm mounted in said housing to drive said worm gear, a bearing sleeve rotatably mounted in said housing chamber, a cutter driving head rotatably mounted in said sleeve and connected with said worm gear for rotation with the same, said cutter driving head connection with the worm gear having provision permitting reciprocation of the cutter driving head along its axis, said cutter driving head having a cam slot, an engaging pin carried by said sleeve and entering said slot, means for securing said sleeve against rotation, all being arranged whereby as said cutter driving head is rotated by said worm gear said pin and cam slot will cause reciprocation of the cutter driving head along its axis, and means for securing said bearing sleeve against rotation having provision for adjusting the position of said bearing sleeve rotationally in said housing.

8. In a device of the character described, a housing, a cutter driving head rotatably and reciprocally mounted in said housing, drive gearing for turning said cutter head, said cutter head having a cam groove, a thumb screw carried by said housing, an engaging pin mounted in said thumb screw to project into said cam groove, means for holding said engaging pin in position, said engaging pin having provisions whereby it may be withdrawn from said cam groove in order that said driving head may be given either a simple rotational movement or a combined rotational and reciprocatory movement as desired.

9. In a device of the character described, a housing, a cutter driving head rotatably and reciprocally mounted in said housing, drive gearing for turning said cutter head, said cutter head having a cam groove, a thumb screw carried by said housing, an engaging pin mounted in said thumb screw to project into said cam groove, means for holding said engaging pin in position, said engaging pin having provisions whereby it may be withdrawn from said cam groove in order that said driving head may be given either a simple rotational movement or a combined rotational and reciprocatory movement as desired, and means for adjusting the position of said thumb screw around the axis of said housing for the purposes specified.

10. In an instrument of the class described, a housing, a cutter driving head,

means for mounting said driving head for simultaneous rotation and reciprocation in said housing, means for turning said cutter head, means for reciprocating said cutter driving head as it is being turned, and a depth gauge passing into said housing and through said cutter driving head, and a milling cutter detachably mounted in said cutter driving head.

10. 11. In an instrument of the class described, a housing, a cutter driving head, means for mounting said driving head for simultaneous rotation and reciprocation in said housing, means for turning said cutter head, means for reciprocating said cutter driving head as it is being turned, a depth gauge passing into said housing and through

said cutter driving head, a milling cutter detachably mounted in said cutter driving head, said depth gauge comprising a 20 threaded pin and a depth gauge tip removably mounted on said pin and provided with an insulating pad for the purposes specified.

12. An instrument of the class described comprising a housing, a worm shaft and 25 worm gear in said housing, a sleeve type milling cutter having opposed cutting points separated by clearance spaces, and means within said housing driven by said worm gear for imparting to said cutter a combined 30 rotational and reciprocatory movement whereby said cutter will be caused to make an undulating cut for the purposes specified.

COLEMAN B. WARREN.
